UNITED STATES PATENT OFFICE.

EDWIN D. LOUNSBURY, OF WHITE PLAINS, AND OTTO ZIMMER, OF BROOKLYN,
NEW YORK.

METHOD OF MAKING COLOR PLATES FOR USE IN LITHOGRAPHY, PHOTO-ENGRAVING, ETC.

Application filed July 26, 1919. Serial No. 313,646.

To all whom it may concern:

Be it known that we, EDWIN D. LOUNSBURY, a citizen of the United States, and a resident of White Plains, county of Westchester, and State of New York, and OTTO ZIMMER, a citizen of the United States, and a resident of the borough of Brooklyn, county of Kings, city and State of New York, have jointly invented certain new and useful Improvements in Methods of Making Color Plates for Use in Lithography, Photo-Engraving, Etc., of which the following is a specification.

This invention has for its object to provide an improved method of making color plates for use in lithography, photo engraving or any other plate making method, and has for its main object to provide certain methods by means of which a color sketch, painting, water or oil-color or object may be accurately reproduced in colors. For this purpose, our invention consists in photographing and making separation negatives of the separate colors of the original color sketch or painting.

The principle underlying the method of the present invention will be understood from the following detailed description of the present preferred manner of practicing this method, the various steps being illustrated in the accompanying drawing in which:

Figure 1 is an elevation of a print taken from a separation negative and corresponding to the color yellow.

Figure 2 is a like view corresponding to the color red.

Figure 3 is a view of the same corresponding to the color blue.

Figure 4 is a like elevation of a print taken from a separation negative corresponding to the color black.

Figure 5 is a view of the print of Figure 1 after retouching.

Figure 6 is a similar view of Figure 2 after retouching.

Figure 7 is a like view of Figure 3 after retouching.

Figure 8 is a similar view of the print of Figure 4 after it has been retouched, and

Figure 9 is an elevation of the complete print.

Referring to the drawing, and as an example; say that you have a sketch to be

reproduced in four colors, then four separation negatives are made. From these negatives photographic prints are then made, as shown in Figures 1 to 4, on porcelain or any hard surface that can be made sensitive so that prints can be made. If paper prints are made it is important in mounting these prints on cardboard or any hard surface as glass or the like to have all the prints register accurately with each other and this may be done by pressing the prints by means of rollers directed all in one and the same direction, so that in all respects the prints are the same or as nearly the same as possible so that the four prints will register accurately with each other. The artist then takes these prints of Figures 1 to 4, retouches each print for the particular color which the prints are made, yellow, red, blue and black, as shown in Figures 1 to 4, and he works up these prints with an air brush, crayon, pencil or paint, painting out white where necessary, the general desire of the artist being that each print for its particular color will most accurately present the color, as illustrated by the retouched prints of Figures 5 to 8 for the respective colors of Figures 1 to 4. After the artist has finished, these prints are photographed through a half-tone or grain screen, making high light half-tone negatives for each color. These negatives are then printed on aluminum, zinc, stone or copper, or other forms suitable for lithography or photoengraving, and etched in the usual manner to produce the finished work as shown in Figure 9.

The method above described has the great advantage over the old lithographic process heretofore known and practiced because the work is practically finished on the photographic prints and when the prints on stone or metal are made they are then ready for proofing. When ordinary, half-tone separation negatives are made and then printed on stone or metal, the artist has to rub out tints and scrape away and put in solids and Ben Day work and very often this work will come up again and the tints put on are not always satisfactory. Another advantage is that we can reduce or enlarge these retouched copies and if necessary can make any size or as many different sizes as desired. Thus an artist having once provided

prints and retouched them for their particular color, these may be stored away without the investment of any large sum of money.

5 The use of our improved method has given advantageous results and lends itself to certain modifications in connection therewith.

What is claimed is:—

10 That method of making color plates for use in lithography which consists in taking separation negatives and making photographic prints from them, one of each color desired, retouching a separate print for 15 each color desired so that the work may be

practically finished on the photographic prints, photographing each retouched print through a half-tone screen to produce a high light half-tone negative for each color, and printing each said last mentioned 20 negative on a sensitized element suitable for photo-engraving.

In testimony that we claim the foregoing as our invention, we have signed our names in presence of two subscribing witnesses.

EDWIN D. LOUNSBURY.
OTTO ZIMMER.
